Primary Examiner—Carmen H. Vales-Lado
Attorney, Agent, or Firm—Lewis E. Massie**[57]****CLAIM**

The ornamental design for a ground inserted helical shaft support, as shown and described.

DESCRIPTION

FIG. 1 is a front elevational view of a ground inserted helical staff support showing my new design;

FIG. 2 is a right side elevational view, the left side being a mirror image thereof; and,

FIG. 3 is a side elevational view in position of use, the broken line showing of an umbrella and ground are for illustrative purposes only.
